UNITED STATES PATENT OFFICE.

ROBERT DUNBAR ANDERSON, OF ETHEL, LOUISIANA.

RAILROAD-SIGNAL.

SPECIFICATION forming part of Letters Patent No. 370,917, dated October 4, 1887.

Application filed March 31, 1887. Serial No. 233,154. (No model.)

To all whom it may concern:

Be it known that I, ROBERT DUNBAR ANDERSON, of Ethel, in the parish of East Feliciana and State of Louisiana, have invented a new and Improved Railroad-Signal, of which the following is a clear, full, and exact description.

My invention relates to a railroad-signal for holding or notifying trains at any telegraph station, and has for its object to provide a simple and positive signal, whereby when a dispatch is received to hold a train the operator may, without leaving the office and while receiving the dispatch, set the necessary signal at the track, and wherein, further, it will be rendered practically certain that the operator will set the signal to stop before writing the order.

The invention consists in the construction and combination of several parts, as will be hereinafter fully set forth, and pointed out in the claims.

Reference is to be had to the accompanying drawings, forming a part of this specification, 25 in which similar letters of reference indicate corresponding parts in all the figures.

Figure 1 is an elevation of the signal set to stop a train. Fig. 2 is a partial central and vertical section of the same. Fig. 3 illustrates 30 the mode of attachment of the clip to the operating-cord and means for retaining the clip and cord in a position at which the signal will indicate "safety." Fig. 4 is a detail view of the forked catch for clip and hook. Fig. 5 is a 35 horizontal section through the lantern, and Fig. 6 is a partial vertical section of the signal with the flag rolled up.

A represents a platform or body of the signal, adapted to be attached at a proper height 40 to any convenient support near the track, in view therefrom either up or down.

A lantern-house, B, is mounted centrally upon the platform, provided with opposing white lenses a, one showing up and the other 45 down the track. Within the lantern-house B a circular turn-table, b, is pivoted in the platform or body A, having a peripheral groove, b'. Centrally upon the said turn-table the lamp C is fixed, and upon opposite sides of 50 said lamp, and also fixed to the turn-table, vertical frames D are provided, adapted to hold

colored glass, the said glass being so positioned that normally the white lenses will not be obstructed, as the colored glass will remain at right angles to said lenses.

55

Longitudinally and centrally beneath the body A a roller, E, is journaled, provided at one end with integral drums d d', and between the inner flange of the inner drum, d, and the opposite end flange of the roller a curtain, F, 60 is hung, preferably red, and provided with a weight, f, longitudinally of the bottom edge, as shown in Fig. 2.

Over the inner drum, d, upon the platform A, pulleys d' are journaled in suitable bearings, 65 the said bearings being so placed as that the faces of the pulleys will be at an inclination from each other and in tangential alignment with the groove b' in the turn-table b. A cord, G, is attached at one end to the drum d, the 70 other end being passed up through an aperture, g, aligning one pulley d', over said pulley, around the turn-table in the groove b', then over the second pulley d', and down through another aligning aperture, g, where- 75 upon the cord is wound a number of times around the drum d and the free end secured thereto. Thus both ends of the cord G are attached to the drum d.

To admit a circulation of air to the lantern-house B, vent-holes b² may be made in the platform A within the four corners of the house, as shown in Fig. 5, and the said house is slotted transversely upon one side for the passage of the cords G, a suitable casing, G', 85 being hinged to said house above the said slot to protect the cord and pulleys d' from the weather, as illustrated in Fig. 6. At each side of the lantern-house apertures h are made in the platform, in which the poles h' of sig- 90

nal-flags may be placed, if desired. An operating-cord, H, is attached to the drum d', which, passing up through an aperture in the platform, is carried over a pulley, h², attached to the outer wall of the telegraph- 95 office, or building in which the telegraph-instrument is situated, and from said pulley h² the cord H passes through a suitable opening in the wall over another pulley, h³, upon the inside of said building, which pulley is pref- 100 erably situated over the operator's desk. The end of the cord is passed through a small aper-

ture in a horizontal bracket, H', secured to the wall, and then provided with a hook, K, the bracket thereby acting as a brake or stop for the said cord. The bracket is so elevated as 5 that when the hook K is in engagement therewith sufficient cord will have played out to allow the curtain F to completely unroll.

Immediately over the operator's desk K', as shown in Fig. 1, a forked bar, k, is horizontally secured, having a convex projection, k', in its forked end. The hook K is drawn down through the forked end of the bar at the convex point, and the manifold-clip M of the operator is attached to the hook, whereby the 15 curtain is rolled and the white light shown, the said manifold-clip being the receptacle in which the operator's blank train-orders are kept. The hook cannot be held in the catch except the clip is attached to the hook to prevent it from passing through the forked bar. Therefore, when the clip is removed by the operator to receive an order, the hook is free and the danger-signal will automatically be set by the weight in the curtain. It will be 20 seen that the clip cannot be taken from the hook without drawing the hook clear out of engagement with the forked bar and then unhooking the clip.

The operation is as follows: An order is received by the operator, who takes down the 30 clip to engross the same. This action frees the cord that holds the flag in a rolled position, and the roller being freed the weight of the curtain or flag will automatically unwind 35 the same. The unwinding of the flag causes the roller to revolve, and the revolution of the roller causes the turn-table inside the lantern-house, upon which the light and colored glass are placed, to revolve a quarter-turn, whereby 40 at once and in an instant there is displayed to full view, both ways of the track, an eighteen-inch flag and colored lights.

It will be observed that an order cannot be taken for a train without taking down the 45 manifold-clip, and the clip cannot be taken down without unwinding the flag, and the flag cannot be unrolled without turning the turn-table upon which the colored glass is placed and giving a colored light, thereby rendering 50 it an impossibility to receive an order for a train and neglect to display the signal, as has

been done, often causing serious loss of life and property.

Suitable guides may be attached to the operating-cord, so that the same will be eased and directed in its ascent when released from the clip. 55

Having thus fully described my invention, I claim as new and desire to secure by Letters Patent—

1. The combination, with the operating-cord of a railroad-signal, of a clip detachably attached to the end thereof within a telegraph-office, and means for retaining said clip and cord in a fixed position, setting the signal at 65 "safety," substantially as shown and described, whereby the signal is automatically operated by the detachment of said clip and release of the cord to display a danger or stop signal, as set forth. 70

2. The combination, with the operating-cord of a railroad-signal, of a clip detachably attached to the end thereof within a telegraph-office, and a forked bar secured above the operator's desk adapted to retain said cord and 75 clip in a position at which the signal will indicate "safety," substantially as shown and described, whereby the signal is automatically operated to display a danger-signal by the detachment of said clip and release of the cord, 80 as set forth.

3. The combination, with a turn-table pivoted in the lantern-house, carrying a lamp and colored glass adapted to register with the lantern-lenses, and a roller carrying a danger-signal flag connected and operating simultaneously with said turn-table, of an operating-cord leading in a telegraph-office through a stop-bracket in said office, a forked bar secured above the operator's desk, and an operator's clip detachably attached to said operating-cord held in position by said bar, substantially as shown and described, whereby the danger-signal in the lantern and upon the roller is rendered certain to be set before the 95 transcript and delivery of the train-message, as set forth. 90

ROBERT DUNBAR ANDERSON.
